UNITED STATES PATENT OFFICE.

WILLIAM S. GUBELMANN, OF BUFFALO, NEW YORK.

VERTICAL-RULING MECHANISM FOR CALCULATING AND LIKE MACHINES.

1,370,499.

Specification of Letters Patent.

Patented Mar. 1, 1921.

Original application filed January 10, 1900, Serial No. 1,004. Divided and this application filed July 17, 1918. Serial No. 245,336.

To all whom it may concern:

Be it known that I, WILLIAM S. GUBELMANN, a citizen of the United States, residing in Buffalo, in the county of Erie and State of New York, have invented certain new and useful Improvements in Vertical-Ruling Mechanism for Calculating and like Machines, of which the following is a specification.

10 This application relates to improvements in vertical ruling mechanism for calculating and like machines, and is a division of my pending application Serial No. 1,004, filed Jan. 10, 1900.

15 Only such of the mechanism herein described as refers to vertical ruling mechanism for calculating and like machines, is claimed herein.

One of the objects of the invention is to 20 provide improved means for ruling vertical lines in calculating and like machines.

Another object is to produce vertical ruling by means of a blade automatically operated at each operation of the machine.

25 Another object is to provide means whereby a pencil or stylus may be held in such relation to the platen that vertical ruling may be produced by rotating the platen.

Another object is to provide a ruling disk 30 whereby a continuous vertical rule line may be produced upon rotating the platen.

Another object is to so position the vertical ruling device that the ruling done thereby may serve as punctuation.

35 Another object is to combine the vertical ruling mechanism with a horizontally shiftable paper carriage so that ruling may be done in different horizontal positions on the sheet.

40 Other objects will be pointed out in the following description and claims.

In the accompanying drawings consisting of five sheets:

45 Figure 1 is a fragmentary top plan view of my improved adding and recording machine, showing the vertical ruling mechanism therefor.

50 Fig. 2 is a vertical longitudinal section of Fig. 1, and showing the adding and recording mechanism of one column or set of keys in the normal or inoperative position.

Fig. 3 is a fragmentary sectional elevation of the printing mechanism of one of the

rows of keys viewed from the side opposite 55 to that shown in Fig. 2.

Fig. 4 is a fragmentary perspective view of the hammer operating mechanism.

Fig. 5 is a horizontal section in line 5—5, Fig. 3. 60

Fig. 6 is a vertical section in line 6—6, Fig. 3.

Fig. 7 is a longitudinal sectional elevation, taken substantially in line 7—7, Fig. 1, and showing particularly the paper carriage and 65 the mechanism whereby different parts of the machine may be thrown into and out of gear.

Fig. 8 is a fragmentary longitudinal sectional elevation taken substantially in line 70 8—8, Fig. 1, and showing the preferred means for producing vertical ruling on the sheet which receives the record.

Figs. 9 and 10 are perspective views showing different means for producing vertical 75 ruling.

Fig. 11 is a vertical section, taken substantially in line 11—11, Fig. 2.

Fig. 12 is fragmentary transverse section, taken in line 12—12, Fig. 2, and showing 80 the means for adjusting the paper carriage lengthwise of the line of printing.

Fig. 13 is a vertical transverse section taken in line 13—13, Fig. 2.

Fig. 14 is a fragmentary perspective view 85 of the units gear segment and controlling arm of the main adding mechanism.

Like letters of reference refer to like parts in the several figures.

General construction.

90

1 represents the main frame of the machine which may be of any suitable construction so as to support the working parts of the machine.

95

2, Fig. 2, represents a number of main dials which register the total of the numbers which are added together. These dials consist preferably of cup-shaped wheels which are numbered on their periphery and 100 are mounted in their proper order on a transverse dial shaft 3, which is journaled in bearings on the main frame, the dials being so arranged that the dial representing the lowest number is arranged on the right hand end of the series and the dials representing the successively higher numbers being arranged successively in their 105

order toward the left from the dial representing the lowest number. The lowest or right hand dial is preferably divided on its periphery into eighths so as to indicate 5 fractions of a cent in eighths, and the remaining dials are graduated on their periphery according to the decimal system into tenths. As shown in the drawings ten total dials are shown and extend from fractions of a cent to tens of millions, but if 10 desired, additional dials may be added to the right and to the left of the series, if it is desired to register smaller divisions of a cent or more than tens of millions. Each 15 of the main total dials 2 is provided on its left hand side with a gear pinion 4, which is rigidly connected therewith, as shown in Fig. 2. The pinion of the fraction wheel has eight teeth while the pinions of the 20 remaining dials are each provided with ten teeth. 5 represents the main registering gear segments, one of which is provided for each of the dials 2 and is adapted to engage with the pinion thereof, for operating 25 the respective dial. Each of these gear segments is arranged in rear of its companion gear pinion and is provided at its lower end with a rearwardly projecting arm 6 which is pivoted loosely on a transverse 30 supporting rod 7. This rod is mounted with its ends on the upper ends of two rock arms 8 which turn loosely with their lower ends on a transverse rock-shaft 9. The rock-arms 8 are connected by a trans- 35 verse bar 10 which compels the two arms to move back and forth together. In the normal position of the gear segments when the machine is at rest these segments are retracted rearwardly out of engagement with 40 the dial pinions of the dials and the segments are elevated so that their lowermost teeth are opposite the spaces between the adjacent teeth of the dial pinions, these spaces being in line with the pivots of the 45 pinions and the gear segments.

The gear segments are yieldingly held backwardly out of engagement with the dial pinions by means of springs 11 connecting the rock-arms 8 with a stationary part 50 of the frame. Fig. 7 shows one of the springs 11 connecting one of the rock-arms 8 with a transverse stationary bar 12 in the rear part of the machine. The gear segments are moved forwardly so that their 55 teeth engage with the dial pinions 4 by means of a shifting rock-arm 13, which is preferably secured to the right hand rock-arm 8 and projects rearwardly. Upon raising the shifting rock-arm 13, the rock- 60 arms 8 are swung forwardly and the gear segments 5 are engaged with the dial pinions, while upon swinging the shifting rock-arms downwardly, the rock-arms 8 are swung rearwardly and the gear segments 65 are disengaged from the dial pinions.

14 represents a cam whereby the gear segments are engaged with the dial pinions. This cam is mounted on the upper portion of a vertically swinging rocking frame 15 which is arranged on the right 70 hand side of the machine. This cam is provided at its front end with an incline or cam face 16 and at its rear end with a concentric face 17. When the cam is in its rearmost or retracted position, its incline 75 stands in rear of a roller or projection 18 on the rear end of the shifting arm 13, as shown in Figs. 2, and 11. Upon swinging the rocking frame 15, so that the cam 14 moves forwardly, the incline of the latter 80 engages underneath the roller 18 and raises the arm 13, thereby moving the arms 8 forwardly. The throw of the incline 16 is just sufficient to engage the teeth of the gear segments with the dial pinions. When 85 the roller 18 has been raised to the top of the incline, the concentric portion of the cam engages with the roller during the continued forward movement of the cam and the latter does not shift the gear seg- 90 ments any farther forward.

When the rear end of the concentric face 17 of the cam passes forwardly from underneath the roller 18, the constant pull of the springs 11 causes the rock-arm 13 to be de- 95 pressed and the rock-arms 8 to be moved rearward, thereby disengaging the gear segments from the dial pinions. Upon now moving the cam 14 backwardly together with the rocking frame 15, this cam does 100 not affect the arm 13 and the parts connected therewith, but is affected by said arm at the last portion of the backward movement of the cam, at which time the back or lower side of incline 16 engages 105 with the roller 18 which lifts said incline, and at the end of the backward movement of the cam, the latter clears said roller and drops behind the same, as shown in Fig. 2, preparatory to again raising the roller 18 110 and connecting parts during the next forward movement of the cam 14.

For the purpose of permitting the front end of the cam to rise so as to clear the roller 18, this cam is pivoted at its rear 115 end to the rear portion of the rocking frame 15. The upward and downward movement of the front end of the cam is limited by means of a lug 19 projecting from the side of the cam and engaging with a slot in the 120 adjacent part of the rocking frame 15, as shown in Fig. 11.

The rocking frame 15 is secured with its lower portion to a transverse rock-shaft 20 journaled in the main frame and provided 125 outside of the frame with a hand crank 21, as shown in Fig. 11, whereby this shaft is rocked and the parts connected therewith are operated.

The gear segments 5 are raised to their 130

highest position by means of a return or lifting-bar 22 which extends transversely underneath all of the arms 6 of the gear segments and which is connected loosely at its rear ends with the transverse rod 7 by lifting plates 23. 24 represents two shifting arms which are mounted loosely at their rear ends on the rock-shaft 20 and which support at their other ends a transverse bar 10 25 which transverse bar is connected at its ends by two links 26, with the lifting plates 23, whereby upon raising the shifting arms 24, the lifting bar 22 is caused to raise the gear segments and the other parts connected therewith resting on said bar. Upon depressing the transverse bar 25, the lifting bar 22 is moved downwardly and the gear segments resting thereon are permitted to move downwardly with the bar until the 15 segments are arrested.

Each of the gear segments is yieldingly held in contact with the lifting bar 22 by a spring 27 which connects the arm of the segments with the transverse bar 25. If the 20 downward movement of the gear segment is arrested while the shifting arms 24 continue to move downwardly, the lifting bar 22 is moved away from the underside of the arm of the gear segment and the spring 27 is strained. The transverse bar 25 is arranged at one end in a segmental notch 28 formed in the front part of the rocking frame 15, shown in Figs. 2 and 11 and its opposite end is arranged in a similar segmental notch 28, 25 formed in a rocking frame 29 which is secured to the operating shaft 20 on the left-hand side of the machine. The rocking frames 15 and 29 together with the operating shaft 20 constitute the main or universal 30 operating frame of the machine.

When the machine is at rest, as shown in Fig. 2, the transverse bar 25 engages with the front side of the notches 28 in the rocking frames 15 and 29. Upon turning the 45 rock-shaft 20 forwardly by means of its handle 21 in the direction of the arrow, Fig. 2, the rocking frames are moved forwardly during the first part of the movement independent of the transverse bar 25. The latter 50 remains at rest until the inclined front end 16 of the cam 14 has raised the arm 13 and moved the gear segments into engagement with the dial pinions, during which movement the rocking frames move idly the extent of their notches 28 along the ends of the 55 bar 26 without disturbing the latter. After the gear segments have been engaged with the dial pinions, the continued forward movement of the rocking frames causes the rear ends of their notches 28 to engage with the bar 25 and depress the same, thereby causing the lifting bar 22 to be moved downwardly and strain the springs 27. This causes all of the gear segments which are 60 free, to be moved downwardly and to con-

tinue their downward movement until they are arrested. During the downward movement of the gear segments, while they are in engagement with the dial pinions, the latter and the dials connected therewith are 70 turned in the direction of the arrow, Fig. 7, until the downward movement of the segments is arrested. The extent which each dial is turned depends upon the position in which the downward movement of its operating segment is arrested. After the segments have been arrested in their downward movement they remain in this position while the rocking frames complete their forward movement. At the end of the forward 80 movement of the rocking frames, the roller 18 of the rock arm 13 drops off from the rear end of the concentric part of the cam 14, thereby allowing the springs 11 to pull the gear segments rearwardly out of engagement from the dial pinions. 85

Upon now turning the rock-shaft 20 backwardly by means of the handle 21, the rocking frames are moved backwardly, until the front ends of the notches engage with bar 25. When the latter is so engaged it is moved backwardly with the rocking frames to the end of their rearward movement which causes the transverse bar 25 to lift the lifting bar 22 and the gear segments 95 which have been depressed into their highest, or normal position. During this upward movement of the depressed gear segments they are out of engagement with the dial pinions, whereby the dials are not turned 100 backwardly with the segments, but remain in their shifted position.

30 represents a number of elbow-shaped controlling arms, which form part of the devices so that the downward movement of the 105 registering gear segments is controlled. One of these arms is arranged along the left-hand side of each gear segment and consists of an upright front part and a horizontal lower part which extends rearwardly from the lower end of the upright part, thereby leaving a clear space in rear of the upright part of the controlling lever, as represented in Figs. 1, 2 and 14. The rear end of the 110 lower part of each controlling arm is mounted loosely on a transverse supporting bar 31, while the upper end of its front or upright part is loosely connected with the upper portion of its companion gear segment. This loose connection permits the controlling arm 115 and the gear segment to swing freely about their individual axes which are arranged parallel but out of line, and also permits the gear segment to move forward and backward into and out of engagement with its 120 companion dial pinion. In the uppermost position of the controlling arms the same bear with their upper ends against a transverse stop bar 32, as shown in Fig. 2, which 125 limits the upward movement of these arms. 130

Each controlling arm is provided on the rear part of its upper end with a locking lug 33, and on the front part of its upper end with a stop lug 34, both of which lugs project toward the left and are preferably stamped out of one piece with the controlling arm.

The operation of the registering devices is controlled by a number of elbow-shaped key levers which are arranged side by side and pivoted to a transverse supporting rod 35. Each key lever is provided with a lower actuating arm 36 which projects forwardly and an upper stop arm 37 which projects upwardly along the left hand side of one of the controlling arms and gear segments, as represented in Fig. 2. Each of these key-levers is provided on the rear side of its stop arm with a locking shoulder 38 which is adapted to engage with the locking lug 33 of the controlling arm when the latter is elevated into its highest position and the key-lever is in its fully retracted position, as shown in Fig. 2. When the parts are in this position, the key lever holds the controlling arm against downward movement and the latter holds the gear segment against downward movement. If the gear segment while so held against downward movement is moved forward into engagement with the adjacent dial pinion and the rocking frames are turned forwardly for depressing the gear segment, the spring 27 of this segment will be strained without however, shifting the segment. At the end of this forward movement of the rocking segments, the roller 18 of the rock arm 13 drops off from the rear end of the cam 14, the gear segment is moved rearwardly out of engagement from the dial pinion and then the rocking frames move backwardly without having shifted the dial.

The upper arm of each key lever is provided on its front side with a vertical series of differential stop shoulders 39, which are arranged step fashion and extend from the upper end of this arm downwardly and forwardly thereon or in other words the stop shoulders 39 are arranged radially out of line with one another and different distances from the pivot of the key lever. These stop shoulders of the key lever are adapted to be moved forwardly into the path of the stop lug 34 on the controlling arm. The stop shoulders are arranged different distances from the stop lug 34 of the controlling arm, so that by moving different stop shoulders of the key lever into the path of the stop lug of the controller arm, the latter and the gear segment connected therewith may be arrested at different points in their downward movement. The uppermost stop shoulder of the key lever is most remote from the stop lug of the controlling arm and therefore requires the greatest for-

ward movement of the key lever, in order to bring this stop shoulder into the path of this stop lug.

The stop shoulders of the key lever are so arranged that the distance from the stop shoulders to the path of the stop lug gradually grows less from the uppermost stop shoulder to the lowermost stop shoulder. The relative position of the different stop shoulders of the key lever is such that when its locking shoulder 38 remains in engagement with the locking lug 33 and the gear segment is simply moved into and out of engagement with its dial pinion, the latter remains at zero, if the same has not been previously moved. But when the key lever has been moved forwardly, so as to disengage its locking shoulder from the locking lug and moves one of its stop shoulders into the path of the stop lug of the controlling arm, the latter arm and gear segment connected therewith will be moved downwardly upon moving the rocking frames forwardly, until the stop lug of the controlling arm strikes the respective stop shoulder of the key lever which stands in its path, whereby the gear segment while turning in engagement with the adjacent dial gear pinion turns the same forward. By turning the key lever forward more or less and moving one or the other of its stop shoulders into the path of the stop lug 34 of the controlling arm, the distance which this arm descends can be varied, thereby varying the number of spaces which its gear segment turns the adjacent dial.

Main number key mechanism.

40 represents the main keys whereby the key levers of the main registering and recording mechanism are operated, and which are guided with their depending stems in the top 41 and bottom 42 of the key-board. As shown in the drawings, nine longitudinal columns of these keys are arranged transversely side by side. The first column on the right hand side of the machine contains seven keys and represents fractions of one-eighth of a cent, the next column toward the left contains nine keys and represents cents and the remaining columns of keys toward the left each contains nine keys and represents progressively higher orders of numbers according to the decimal system, so that the registering keys in the last or left hand column represent hundreds of thousands of dollars.

The lowest numbers of the several columns of keys are arranged transversely in a row on the rear part of the key-board and the corresponding higher numbers of the several columns are arranged likewise in transverse rows and progressively in their order toward the front end of the key-board.

Each of the registering keys is yieldingly held in an elevated position by a spring 43 surrounding the stem of the key and connected at its upper end to the key and bearing with its lower end against the bottom of the key-board. The upward movement of each key is limited by a shoulder 44 formed on the upper part of its stem and engaging with the underside of the top of the key board.

The downward movement of all of the keys is substantially the same, but the arrangement of each column of keys lengthwise of the lower actuating arm of each key lever causes the keys to bear against the lever at different distances from its pivot so that by depressing different keys the same distance, the key lever will be turned different distances. The keys having the lowest numbers bear against their respective key levers nearest the pivot and consequently the levers are thereby thrown the greatest distance, and the uppermost stop shoulders are shifted in to the path of the stop lug 34 of the respective controlling arms. The throw of each key lever upon depressing any one of its keys is so adjusted, that the proper stop shoulder on its upper arm is moved into the path of the stop lug 34 of the controlling arm and the downward movement of the respective gear segment is arrested after having turned the adjacent dial gear pinion a number of spaces corresponding to the number of the key which is depressed.

Loose connection for segments.

The loose connection between each controlling arm and its gear segment, heretofore referred to, is shown in its simplest form in the connection between the controlling arm and the gear segment, which are controlled by the initial or lowest column of registering keys. As shown in Figs. 1 and 14, the loose connection between the controlling arm and the gear segment of the lowest registering device consists of upper and lower guide lugs 45 and 46 arranged on the upper end of the segment and bearing against the upper and lower guide faces 47 and 48, which are formed on the upper end of its companion controlling arm. As the controlling arm and segment rise and fall, the guide lugs of the segment slide back and forth on the guide faces of the arm. The guide faces are so constructed that the back and forth movement of the segment on the arm is radially with reference to the dial pinion in all positions of the segment. By so forming the guide faces of the arm, the gear segment can be engaged with and disengaged from the dial pinion in all positions of the segment without disturbing the position of the dial pinion. The construction of the loose connections between

the controlling arms and gear segments of all of the higher registering devices above the fractional registering device are combined with carrying devices, whereby each registering dial, upon making one complete turn, causes the next higher dial to be turned forward one space, thereby carrying up a number from one column to the next higher column. The loose connections between the controlling arms and the segments and the carrying mechanism of the higher registering devices are constructed as follows:—

As shown in Figs. 1 and 2, each controlling arm is provided at its upper end with upper and lower guide faces 47 and 48 and its lower guide face is engaged by a lower guide lug 46 on the adjacent gear segment, the same as in the coupling between the controlling arm and segment of the initial registering device. The gear segments of the higher registering devices are each provided with an upper guide lug 49 which is adapted at times to bear against the upper guide face 47 of the companion controlling arm in substantially the same manner in which the upper guide lug 45 of the fractional gear segment bears against its companion arm, the only difference being that the upper guide lug 49 of the higher gear segments are held out of engagement and separated by a space from the upper guide face of the companion arm when no number is carried from a lower to a higher registering device. The upper guide lug 49 is held in this elevated position above the adjacent guide face by a rocking latch 50 which is arranged in a notch in the rear side of the gear segment and which normally projects toward the left and engages with the upper guide face 47 of the adjacent controlling arm, as shown in Fig. 2.

During the ordinary up and down movement of each higher controlling arm and gear segment, the latter is guided by its lower guide lug 46 and the locking latch 50 engaging with the lower and upper faces of the adjacent arm, this movement being the same as the movement of the controlling arm and gear segment of the fractional registering device. Normally the downward movement of the controlling arm is determined by the position of its companion key lever and this arm in turn controls the extent of the downward movement of the gear segment. When, however, the locking finger 50 is withdrawn out of engagement from the upper guide face 47 of the arm, the companion gear segment is capable of moving downward independent of the arm until the upper guide lug 49 engages with the upper guide face of the arm. The extent of this independent movement of the gear segment with reference to its companion arm is equal to one tooth or space of the segment, so that by this means the gear

130

segment is enabled to turn the dial pinion one space more than the position of the key lever permits the same to move.

The withdrawal of the locking latch of each higher registering device is controlled by the next lower registering device and the withdrawal of each latch is effected when the next lower registering device has made one complete turn and arrived at zero. Each of the locking latches is pivoted on the right hand side of its adjacent gear segment, so as to turn transversely with reference to the latter. The latch is turned toward the left into its operative position by a spring 51, the movement in this direction being limited by a shoulder 52 arranged on the latch and bearing against the right hand side of the gear segment. 53 is an upright trip plate connected with the lower end of each latch and arranged normally at right angles or nearly so to the adjacent gear segment, when the latch is in its operating position. 54 represents a number of upright trip arms, each of which is controlled by a lower registering device and which turns the locking latch of the next higher registering device into an inoperative position. This arm is mounted loosely with its lower end on the supporting bar 35 and is provided at its upper end with a rearwardly and forwardly projecting hook 55, and in front and below said hook with a bend forming a bearing finger 56. 57 represents trip cams arranged on the left-hand side of each registering dial pinion and connected with the adjacent pinion and dial, but separated from the pinion by an intervening space or groove. The face of each of these cams may begin at its lowermost point near the axis thereof and then extend outwardly in a spiral line terminating with its highest point in line with its lowermost point with which it connects abruptly. The trip cam of the fractional registering device has its face divided into eight parts, each part of which except the first is arranged one-eighth of a space farther from the center of the cam than the preceding part, while the trip cams of the higher registering devices each has its face divided into ten parts, each part except the first being arranged one tenth of a space farther from the axis of the cam than the preceding part. Each of the trip arms 54 extends upwardly along the right-hand side of the trip cam of a lower registering device and its shoulder 56 engages with the face of this cam, while the hook 55 at its upper end extends toward the left and is adapted to engage with the trip plate 53 of the next higher registering mechanism. In the initial position of each trip arm, its shoulder 56 engages with the lowest part of its trip cam, as represented in Fig. 2. As the trip cam is turned in the direction of the arrow, Fig. 2, at the same time that its

dial and gear pinion are moved forwardly by the adjacent gear segment during the adding operation, the trip arm is moved backwardly by the gradually rising face of the trip cam. During this backward movement of the trip arm, its hook engages with the trip plate 53 of the next higher registering device and is deflected toward the right thereby, the hook being sufficiently elastic for this purpose. After the hook has passed in rear of said trip plate, the hook owing to its resilience springs back to its normal position, so as to stand behind said trip plate. When the shoulder of the trip arm reaches the highest part of the face on the trip cam the trip arm has been shifted to its rearmost position. Upon now turning this cam forwardly another space together with its companion dial and pinion, the highest part of the cam is carried from underneath the shoulder of the trip arm and the latter is moved forwardly over the abrupt face of the cam until its shoulder 56 again engages with the lowest part of the cam face. During this movement of the trip arm, its hook strikes the rear side of the trip plate 53 of the next higher registering mechanism and turns the same forwardly, thereby disengaging the locking latch from the adjacent controlling arm and permitting the gear segment carrying the trip plate to move forward one space. The forward movement of the trip arm is effected when the dial to which its trip cam is connected has made one complete rotation and again stands at zero, whereby the addition represented by this complete rotation is carried to the next higher registering device. The forward movement of the trip arm is effected quickly by a spring 58, which connects with a stationary cross bar 59 arranged in front of the trip arms. The trip plate 53 of each registering device is so arranged and is of such length that the hook of the next lower trip arm can engage with the rear side of the plate, for disengaging its latch in any position of the gear segment carrying the plate, and in order to accomplish this engagement it is obvious that cams 57 should be constructed so as to give arms 56 the proper throw. If a gear segment is locked in its highest position by reason of none of its companion keys having been depressed, the withdrawal of its latch from the controlling arm simply permits the gear segment to drop one space and turn its companion dial pinion forward one space, while in engagement therewith, the movement of this dial representing one number carried up from the next lower dial. If any one of the keys of the key levers has been depressed, so as to release the gear segment and permit the same to move downwardly for effecting an addition, and if during this time the next lower registering device has

made a complete turn, so as to require the carrying up of a number from the next lower registering mechanism, the latch of the higher registering device will be withdrawn while the same is effecting its addition, thereby causing the segment to descend and turn its dial one space in addition to the spaces corresponding to the depression of its respective key.

- 10 When the locking latch has been withdrawn so as to permit a gear segment to move downwardly one space farther than its controlling arm, the latch remains in this position during the subsequent upward movement of the arm and the segment until the upward movement of the arm is arrested by striking the stop bar 32 and the gear segment continues its upward movement independent of the arm the extent of one space. The gear segment has now reached its highest position and its latch is again swung automatically by its spring over the controlling arm. The controlling arm and gear segment now remain in this relative position until another number is to be carried up from the next lower registering device.

When the controlling arm has been retracted to its highest position, the adjacent key lever is moved into its normal retracted position, so that its locking shoulder 38 engages with the locking lug 33 of the controlling arm and locks the latter against downward movement. The return movement of each key lever is preferably effected by a spring 60 which connects the upper arm of the key lever with the transverse shaft 9, as shown in Fig. 2, or with some other convenient part of the machine. The lower guide lug of the gear segment is not absolutely necessary because the weight of the parts connected with the controlling arm and arranged in rear of its pivot is sufficient to raise the arm, but it is preferable to employ this lower guide lug 46 on the gear segment because it compels the arm to raise with the gear segment and avoids displacement of these parts with reference to each other, and also serves as a stop to limit the upward movement of the gear segment.

- The gear pinion and the coöperating gear segment of the fractional registering device are so constructed that the fractional dial makes one rotation whenever it is moved forward eight spaces. After the fractional dial has made one rotation the whole number represented by this rotation is transferred by the first carrying device from the registering device which represents cents. The complete turns of each of the following registering devices are in like manner carried or transferred to the next higher dial by the respective carrying device. The dial which records the highest number, in this instance the millions of dollars is preferably

operated only by the adjacent carrying device of the next lower dial and is incapable of being operated directly from the keyboard because it is not provided with a key operating mechanism.

The mechanism whereby the dials are all turned back to zero or the place of beginning after the addition of numbers has been completed is constructed as follows:

61 represents a series of feeling rock levers which are adapted to shift the key levers, so as to permit the gear segments to descend the proper distance for resetting or restoring the main registering dials to zero. One of these shifting levers is mounted loosely on the supporting bar 35 adjacent to the left hand side of each of the key levers and is provided on its upper arm with a forwardly projecting feeling finger 62 and with a shifting finger 63 which extends behind the upper arm of the adjacent key lever. The feeling levers have their fingers arranged in rear of the total cams 57 and each of these levers is turned so that its upper arm moves backwardly by the upper arm of the adjacent key lever engaging with the shifting finger 63 of the feeling lever. 64 represents a transverse pull bar arranged in rear of the lower arms of the feeling levers and connected with each of the latter by a pull spring 65, as represented in Figs. 2 and 11. This pull bar is connected at its ends to the lower ends of two depending pull or rock arms 66, which are secured at their upper ends to the rock shaft 9, as shown in Fig. 11. Upon turning this rock-shaft, so as to swing its depending pull arms backwardly the feeling levers are turned by means of the springs 65 so as to move the upper arms of these levers forwardly. This movement of the rock-shaft 9 is effected by a cam 67, which is mounted on the left-hand side of the rocking frame 29 and which is constructed substantially the same as the cam 14 which is mounted on the rocking frame 15. As shown in Figs. 7 and 13, this cam is pivoted at its rear end by a transverse pin to the rear portion of the rocking frame 29 and is provided at its front end with an incline or cam face 68 and in rear of the incline with a concentric face 69. The cam 67 is pivotally supported on the rocking frame 29 in the same manner in which the like cam 14 is pivoted on its corresponding rocking frame 15. The cam 67 can be raised and lowered with its front end into an inoperative or operative position, this movement being limited by means of a lug 70 arranged on the cam as shown in Fig. 11, and projecting into a slot 71 in the adjacent rocking frame in the same manner in which the movement of the cam 14 is limited.

72, Figs. 7 and 11, represents a rearwardly projecting rock-arm secured to the rock

shaft 9 and provided at its rear end with a roller or projection 73 which is adapted to be engaged by the cam 67 for turning the rock shaft 9. When numbers are being 5 added with the machine, the cam 14 is depressed, as shown in full lines, Fig. 2, so as to be in a position when moved forwardly by the rocking frame 15 to engage the roller on the arm 13, for moving the gear segments 10 into engagement with the dial pinions, and during this time the cam 67 is lifted into the position shown in full lines, Fig. 7, so that when the rocking frame 29 is moved forwardly the cam 67 will clear the rollers 15 73 of the rock arm 72 and not disturb the rock-shaft 9 and the parts connected therewith.

If it is desired to restore all of the total 20 dials 2, to zero, the cam 14 is raised into its inoperative position, shown by dotted lines 14 in Fig. 2, and the cam 67 is lowered into its operative position, as shown by dotted lines 67^a in Fig. 7. Upon now turning the rock-shaft 20 by hand so as to move both 25 rocking frames 15 and 29 forwardly, the cam 14 passes over the roller 18 of the arm 13 without disturbing the same, but the inclined front of the cam 67 engages with the roller 73 on the rear end of the rock-arm 30 72 and raises the same until this roller engages with the concentric part 69 of this cam. By this movement of the arm 72, the rock shaft 9 is turned in the direction for moving its depending arms 66 rearwardly 35 and pulling the springs 65 rearwardly. This pull on the springs 65 causes the feeling levers to be turned until the feeling fingers of their upper arms engage with the spiral surfaces of the trip cams. After the feeling 40 fingers bear against these cams, their movement is arrested and the continued backward movement of the pullbar 64 simply stretches the springs 65 until the bar reaches the end of its backward movement. The feeling 45 finger of each feeling lever engages with that part of the surface of the adjacent trip cam which is directly opposite the feeling finger, and as these trip cams are turned with the adjacent dial they present different parts 50 of their spiral surfaces to the opposing feeling fingers, which causes the forward movement of the upper arms of the feeling levers to be arrested in different positions when swung forwardly. During the forward 55 movement of the upper arm of each feeling lever, its shifting finger 63 engages with the rear side of the upwardly projecting arm of the adjacent key lever and moves this arm forwardly. The construction of the parts 60 is such that the spiral surfaces of the trip cam bears a definite relation to the step-shaped series of stop shoulders on the upper arm of the key lever. When the feeling finger of the feeling lever, upon 65 being moved forwardly, bears against the

lowest key-lever-stop controlling part of the adjacent trip cam, the adjacent key lever is carried simultaneously forward with the feeling lever the greatest distance and its uppermost stop shoulder is carried into the 70 path of the stop lug of the controlling arm. The succeeding parts of the spiral surface of the trip cam are so constructed that they rise progressively higher and arrest the forward movement of the feeling lever when the 75 same has carried the adjacent key lever with its corresponding stop shoulder into the path of the stop lug of the controlling arm. This forward movement of the feeling lever and that of the upper arm of the key lever is 80 gradually reduced as the progressively higher parts of the trip cam are presented to the feeling finger, and when the highest part of the trip cam is presented to the feeling finger, the feeling lever is prevented 85 from moving forward at all and the upper arm of the key lever is not moved with its locking shoulder out of engagement with the locking stop of the controlling arm and consequently the companion gear segment connected therewith is held against downward movement. After the rocking frames 15 and 29 have been turned forwardly sufficiently to engage the several feeling fingers of the 90 feeling levers with their respective trip cams, 95 the rear ends of the segmental notches 28 in the rocking frames engage with the cross bar 25 and depress the same, thereby moving the lifting bar 22 downwardly and at the same time pulling down the springs 27. This 100 downward pull on these springs causes each spring to pull its respective gear segment down as far as possible, and after the downward movement of the segment has been arrested the continued downward movement of 105 the cross bar 22 together with the rocking frames simply stretches these springs until this bar reaches the end of its downward movement. If a gear segment is locked in its uppermost or zero position its spring 27 will be 110 stretched its fullest extent, whereas, if a gear segment moves downwardly more or less before it is arrested by its shifted key lever, its spring 27 will be stretched less in proportion. This downward movement of 115 the gear segments which are free to move in this direction takes place while the gear segments are in their retracted position and out of engagement from the dial pinions, so that the dials are not affected by this movement 120 of the segments.

After the rocking frames have reached the end of their forward movement and the roller 73 has dropped off from the rear end of the concentric portion 69 of the cam 67, 125 the gear segments are moved forwardly by hand operated mechanism into engagement with their respective dial pinions and are held in this position during the entire subsequent backward movement of the rocking 130

frames which is effected by hand operated mechanism. During the backward movement of the rocking frames, the gear segments are raised to their highest positions, 5 while in engagement with the dial pinions by the rod 22 and connecting parts and turn the dials backwardly. At the end of the upward movement of the gear segments the latter are released, so as to permit them to move 10 into their retracted position, out of engagement from the dial pinions.

During this operation, those gear segments which are held or locked in their highest positions, by reason of their dials being at zero, are simply moved forward at 15 the end of the forward movement of the rocking frames, so as to engage with their respective dial pinions and are again moved backwardly out of engagement therefrom at 20 the end of the forward movement of the rocking frames, without disturbing their respective dials. Each of the unlocked gear segments is moved downwardly a number of spaces corresponding to the number which is 25 registered on its dial, the extent of this movement being controlled by the companion trip cam which arrests the forward movement of the key lever, through the medium of its feeling lever, when the proper 30 stop shoulder of the key lever has been presented to the controlling arm.

Upon now moving the gear segments forwardly in their variously depressed positions and then raising them to their highest 35 position, each depressed gear segment will turn its dial backward the same number of spaces that the gear segment was depressed. Inasmuch as each gear segment was permitted to descend by its trip cam, feeling lever 40 and key lever the same number of spaces as the number indicated on its dial, the gear segment subsequently moves upwardly the same number of spaces before reaching its highest position, thereby turning its dial 45 backwardly the same number of spaces and restoring the same to zero. When all of the dials have been returned to zero, the shoulders 56 of all the trip arms engage with the lowest parts of all of the trip cams 57.

50 The mechanism whereby the positions of the cams 14 and 67 are reversed preparatory to restoring the dials to zero is constructed as follows:

The cams 14 and 67 drop into their operative position by gravity. Each of these cams is provided in rear of its pivot with a tail 55 75 which is depressed when it is desired to lift the respective cam into its inoperative position.

60 76 is a shifting lever which is pivoted at its lower end and is normally turned so that its upper end is disengaged from the rear side of the tail on the cam 14 by a spring 77 as shown in Fig. 2. The member 76 projects in rear of the main frame so as to be acces-

sible for manual operation. 78 is a shifting lever which is pivoted between its upper and lower arms and arranged with its upper arm in rear of the tail on the cam 67 and normally held in engagement therewith by a 70 spring 79, as shown in Fig. 7. 80 represents an elbow lever pivoted below the bottom of the keyboard, as represented in Fig. 7. 81 represents a main line or cord which is connected with the lower arm of the elbow lever 80 and which is provided at its rear end with two branches 82 and 83. The branch 82 connects with the shifting lever 76 above its pivot, and the branch 83 connects with the shifting lever 78 below its pivot. 84 represents a total or shifting key having a depending stem which is guided in top and bottom of the key-board and which bears with its lower end against the upper arm of the elbow lever 80. Upon depressing the key 85 84, the elbow lever 80 is turned, so as to draw the cords or lines 81, 82 and 83 forwardly, thereby moving the upper end of the shifting lever 76 into engagement with the tail of the cam 14 and lifting the same 90 into an inoperative position, while the shifting lever 78 is moved rearwardly with its upper arm from the tail of the cam 67, thereby allowing the latter to drop into its 95 operative position. Upon depressing the gear segments while the parts are in this shifted position, the segments move downwardly out of engagement with the dial pinions. After the gear segments have been depressed they are moved forwardly into engagement with 100 their respective dial pinions by an elbow lever 85 which is connected with its lower arm by a line or cord 86 to the rod or bar 7, as shown in Fig. 7, or to one of the rock arms 8. The elbow lever is turned in the proper direction for this purpose by a shifting key 87 having a depending stem which is guided in the top and bottom of the key-board and which bears against the upper arm of the elbow lever 85. After the gear 105 segments have been moved forwardly into engagement with the dial pinions, while in the depressed position, the gear segments are retained in forward position, and at the same time raised until they reach their uppermost 110 position, whereby the dials are turned to zero. The shifting key 87 is now released which permits the spring 11 to move the gear segments rearwardly out of engagement with the dial pinions. The key 84 is 115 also released, thereby permitting the shifting levers 76 and 78 to resume the positions shown in Figs. 2 and 7, leaving the machine in position to resume adding.

Each of the dials is normally held against 120 turning by means of a detent pawl 103 which engages with the front side of its companion gear pinion, as shown in Fig. 2. The pawls 103 of the several gear pinions are mounted on a transverse pawl bar 104, 130

- which is supported at its ends by means of two pawl arms 105, which turn loosely upon the supporting rod or bar 35 of the key levers. The pawl arms are moved rearwardly for engaging the pawls of the bar 104 with the gear pinions by means of springs 106. These springs are connected loosely at their rear ends to the rock-shaft 9 and at their front ends to the pawl arms 105.
- 10 During the forward movement of the gear segments preparatory to turning the dial pinions, the detent pawls are swung forwardly out of engagement with the dial pinions by means of two shifting rods 107 which are connected at their rear ends to opposite ends of the transverse rod 7 or some part moving therewith and each of which is provided at its front end with a fork or bifurcation 108, which engages with 20 a pin or shoulder 109 on the pawl arm arranged on the adjacent side of the machine. As the gear segments move forward into engagement with the gear pinions the shifting rods 107 move the detent pawls 103 out 25 of engagement with the dial pinions and when the gear segments move backwardly the detent pawls are again engaged with the dial pinions by the springs 106, Fig. 7.

Recording mechanism.

30 For the purpose of recording the numbers which are added together by the above described mechanism a recording mechanism is provided which is constructed as follows:—

140 represents a printing roller or platen which is arranged transversely in the upper, rear part of the machine and under the lower side of which the sheet or other article is placed which receives the record. 141 represents a number of type segments which are arranged transversely side by side below the platen and which are pivoted at their front ends to the supporting bar 31 upon 40 which the rear ends of the controlling arms 30 are pivoted. Each of these type segments is provided at its rear end with a segmental row of type carriers 142, which are capable of moving radially back and forth 45 on the type segment.

Each of the type carriers is provided at its rear end with a type and is guided upon the type segment by means of screws or rivets 143 secured to the type carrier and 50 arranged in radial slots 144 formed in the type segment, as shown in Figs. 2 and 3. Each of the type carriers is held in its inward or retracted position by means of an S-shaped spring 145, which is arranged between the carrier and the type segment and is secured with one end to the carrier and with its other end to the type segment. Upon raising or lowering the type segment any one of its type can be brought to the 60 printing point or line, and upon striking 65

the back or inner end of the type carrier, when the same is in line with the printing point the type carrier will be driven outwardly and its type will produce an impression on the sheet supported by the platen. 70 After the carrier has received the blow for driving the same against the platen, the carrier is again quickly retracted to its innermost position by means of its spring.

Each of the type segments is connected 75 with one of the controlling arms, so that upon depressing a controlling arm and the registering gear segment connected therewith, the companion type segment will be raised and present one of its type to the 80 printing point.

For convenience in operating the machine, the keys are separated a considerable distance on the key-board and in order to produce a compact record, the printing segments are arranged closer together than the keys and the registering mechanism. In order to permit of this arrangement, each type segment and its corresponding controlling arm are connected by a connecting arm 85 90 146 as represented in Figs. 1 and 2. The connecting arms of the central controlling arms and type segments are comparatively straight, but the connecting arms of the outer type segments and controlling arms 95 are arranged obliquely, the degree of this obliquity gradually increasing from the central type segments and controlling arms in opposite directions toward the outer type segments and controlling arms, as represented in Fig. 1. The connecting arms 146 of the outer controlling arms are arranged in the spaces behind the upright parts and above the horizontal parts of the controlling arms, thereby permitting the inner controlling arms to move up and down without interfering with the connecting arms 100 105 146 of the outer controlling arms.

The types on each type segment are arranged to correspond with the teeth and 110 numbers of its companion gear segments and registering dial, the zero type being at the upper end of the series and the progressively higher digits arranged in their order downwardly from the zero type. When 115 the registering gear segment is in its highest position it presents its zero tooth to the dial pinion, and the type segment which at this time is in its lowest position presents its zero type to the printing point. Upon 120 depressing a gear segment so as to present one of its higher teeth to the dial pinion, its companion type segment is raised proportionally and presents a corresponding higher numbered type to the printing point. 125

147 represents a number of hammers whereby the type carriers are struck for driving the type against the platen. One of these hammers is arranged adjacent to each type segment and is provided with a 130

head which is arranged in front of the series of types and in line with the printing point of the platen. Upon shifting the type segment so as to bring one or another of its type carriers to the printing line and then operating the hammer, the latter delivers a blow against the inner end of the particular carrier which is at the printing point and produces an impression of its type on the platen. The several hammers are pivoted on the transverse rod 12, arranged in rear of the segments; and each of the hammers is yieldingly held in its forward position by a spring 148 connected at its lower 10 end to a cross bar 149 and at its upper end to a depending arm 150 on the hammer.

151 represents a vertically movable trip bar or rod which is arranged transversely below the hammers and whereby the latter are operated. This bar is supported at its ends upon the rear ends of rock arms 152 which turn loosely with their front ends on the rod 31 supporting the type segments and controlling arms.

153 represents a number of hammer or trip pawls, whereby the hammers are retracted preparatory to delivering a blow against the type carriers which are at the printing point. One of these pawls is arranged adjacent to each hammer and pivoted loosely at its lower end to the trip bar 151, and its upper end is provided on its rear side with a downwardly facing hook or shoulder 154, and above said shoulder 30 with a trip face 155, as shown in Figs. 3 and 6. Each of the hammers is provided in front of its pivot adjacent to the upper end of the hammer pawl with a lower trip lug or shoulder 156 and an upper trip lug or shoulder 157. When the parts are at rest, the hammer pawl 153 is raised into its highest position and the hammer is in its normal position with its lower trip lug 156 below and in rear of the hook of the hammer pawl and with its upper shoulder 157 in rear of the trip face of the hammer pawl, as 40 represented in Figs. 2, 3, and 4.

Upon shifting the hammer pawl rearwardly, while the parts are in this position, 50 so that its hook overhangs the lower shoulder 156 of the hammer, and then pulling the hammer pawl downwardly, the hook of the hammer pawl engages with the lower shoulder of the hammer and turns the same 55 so that its head is retracted from the type carrier at the printing line. As the hammer moves downwardly with the hammer pawl, the upper shoulder of the hammer comes into engagement with the trip face 60 of the hammer pawl and during the continued downward movement of the hammer and its pawl, this upper shoulder gradually crowds the hammer pawl forwardly with reference to the hammer by reason of the 65 hammer and its pawl swinging on different

centers. During the last portion of the downward movement of the trip bar 151 and the hammer pawl mounted thereon, the pawl is crowded forwardly by the upper shoulder 157 of the hammer to such an extent that its hook is disengaged from the lower shoulder 156 of the hammer, thereby liberating the latter and permitting its spring 148 to throw the same quickly and deliver a blow against the type carrier 70 at the printing line. The trip bar 151 now rises and carries the hammer pawl into its highest position, preparatory to again engaging the hammer for depressing the same.

158 represents a number of upright shifting arms whereby the hammer pawls are moved rearwardly, so that their hooks engage with the lower shoulders of the hammers. One of these arms is arranged adjacent to 80 each hammer pawl, as shown in Figs. 3, 4 and 6 and is pivoted at its lower end on the trip bar 151, and its upper end is provided with a roller or projection 159 which bears against a hammer cam 160 on the lower part 90 of the adjacent type segment, as shown in Fig. 3. This hammer cam is provided at its upper end with a receding or low portion, an inclined portion arranged below the low portion, and a concentric or high portion 95 arranged below the inclined portion. Each shifting arm 158 is moved forwardly and its roller is yieldingly held in engagement with the adjacent hammer cam by a spring 161 connecting said arm with a cross bar 162 secured to the rock arms 152. The backward movement of each hammer pawl with reference to its companion shifting arm, is limited by means of a stop 163 secured to the upper portion of the hammer pawl and 100 engaging with the front side of the shifting arm, as represented in Figs. 3, 4 and 5.

Each hammer pawl is yieldingly held in its rearmost position with reference to its shifting arm by means of a C-shaped spring 110 164 secured with its ends, respectively, to the hammer pawl and its shifting arm, as shown in Figs. 2, 3 and 4. In the lowermost position of a type segment the receding part of its cam is presented to the roller of 115 the shifting arm 158, which permits the hammer pawl to be retracted into its foremost position, as represented in Fig. 2. Upon depressing the trip bar 151 when the parts are in this position, the roller 159 is 120 not engaged soon enough by the incline of the cam 160 to engage the hook of the hammer pawl with the lower shoulder of the hammer, before the hook has passed below this shoulder but instead, the trip face 125 of the hammer pawl slides idly against the shoulder 156 without retracting the hammer, whereby no impression of the particular type at the printing line is produced. If the type segment is raised, so as to pre- 130

sent one of its lower types to the printing point or line, the incline of its cam, during the first part of the upward movement of the segment, moves the shifting arm 158 rearwardly together with the hammer pawl 153 yieldingly connected therewith, so that the hook of the hammer pawl stands over the lower shoulder 156 of the hammer. Upon now depressing the pawl 153 the hammer 10 will be retracted and released near the end of the downward movement of the pawl and will be quickly swung up by the spring 148, thereby delivering a blow against the type at the printing point and producing an impression thereof. 15

The incline 160 of the type segment cam is so constructed that it throws the hammer pawl backwardly into an operative position when the segment is raised one digit space, 20 and during the continued upward movement of the segment, the hammer pawl is held in this operative position by the high concentric part of the segment cam. By thus constructing the type segment cam its companion hammer pawl is not shifted when the segment is not raised and its zero type remains at the printing line, but the hammer pawl is shifted into an operative position for producing an impression, if the type 25 segment is raised one or more digit spaces and presents any one of its digits higher than zero to the printing line.

Automatic printing of zero.

35 165 represents a number of transfer or coupling fingers which enable the ciphers in a number to be printed automatically. One of these transfer fingers is secured to each of the shifting arms 158, as represented in Figs. 3 and 4, and extends laterally toward 40 the right therefrom into engagement with the shifting arm of the next lower hammer pawl, as represented in Fig. 13. If any one of the printing segments remains in its 45 lowest position, so that its cipher remains at the printing line and the next higher printing segment has been raised for printing a higher number or digit, the transfer finger of the higher hammer shifting arm 50 158 while being moved rearwardly by the cam of its companion printing segment, is caused to engage with the shifting arm 158 of the next lower hammer pawl and shift the latter backwardly, so that its hook is 55 carried backwardly over the lower shoulder of the companion hammer. Upon now depressing the trip bar 151, the higher hammer pawl 153 is coupled with its hammer, and the next lower hammer pawl is also coupled with its hammer, whereby an impression of the cipher or zero type on the lower segment is produced on the platen at the same time that the next higher number is printed on the platen. 60

If two ciphers occur in succession in the 65 body of a number the shifting arm to the left of the highest order printing segment to be operated for printing a zero sets the hammer mechanism of said highest zero-printing segment by means of the transfer finger 70 of said shifting arm and the shifting arm of said highest zero-printing segment in turn by means of its transfer finger sets the hammer mechanism of the printing segment of next lower order, etc. This 75 operation of producing an impression of the cipher type is effected automatically and renders it possible to print any number of ciphers in succession in the body of a number because the hammer operating 80 mechanism of each segment which remains standing with its upper type at the printing line is controlled by the hammer operating mechanism of a higher type segment and in turn controls the hammer operating 85 mechanism of the next lower type segment, if the next lower segment presents a cipher to the printing line.

Only the ciphers below the highest digit 90 in the number to be recorded are thus printed automatically because the printing of a digit depends upon the upward movement of a printing segment, thereby avoiding the printing of ciphers ahead of the highest digit in the number to be recorded. The 95 hammer shifting device of the segment which prints the numbers representing units of cents is preferably not provided with a transfer finger to operate on the hammer shifting device of the segment which prints 100 fractions of a cent, because it is proper that the space to the right of the lowest integer shall remain blank when no fraction is recorded therein.

The carrying bar 151 is raised by one or 105 more springs 166 which connect this bar with the transverse rod 12, and the upward movement of the bar 161 is arrested when the hammer operating pawls reach their highest position by a transverse bar 167 110 which is engaged by the rear ends of the rock arms 152. 168 represents a coupling hook, whereby the hammer trip devices are depressed. This hook is pivoted with its upper end to the trip bar 151 and its lower 115 engaging end is provided with a notch having upper and lower shoulders.

In the lowered position of this hook its notch engages with a cross bar 169 which is connected with the rock arms 24, as represented in Fig. 2, so that the hook and hammer operating devices connecting therewith are actuated from the rocking frames 15 and 29, through the medium of the rock arms 24. In the rearmost position of the rocking 120 frames, the front ends of their notches 28 bear against the front side of the bar 25 to which the gear segments are yieldingly con- 125

nected and the cross bar 169 bears against the rear or upper shoulder of the notch of the hook 168, as represented in Fig. 2.

Upon swinging the rocking frames forward, the incline of the cam 14 first raises the rock arm 13 and shifts the gear segments into engagement with the dial pinions, and after the segments have been so shifted, the rear shoulders of the notches 28 in the rocking frames engage with the cross bar 25, so that thereafter this bar is carried downwardly with the rocking frames and the gear segments are depressed. During this downward movement of the bar 25 with the rocking frames, the companion bar 169 moves down idly in the notch of the hook 168 until this bar engages with the lower or front shoulder of this hook. After the cross bar 169 engages with the lower shoulder of the notch of the hook, the latter and the hammer operating devices connected therewith are moved downwardly with the rocking frames until these frames reach the end of their downward movement. During the last portion of the downward movement of the rocking frames the hammer pawls are disengaged, as before described, from the retracted hammers, whereby the latter are released and strike the type carriers which are at the printing line. By this means, the blow of the hammers is delivered after the registering of the numbers has been effected on the dials and the type segments have been shifted into their proper position for recording the respective number.

The hammers do not follow the type carriers to the end of their outward movement but are stopped short, after delivering a blow against the inner ends of the carriers by their depending arms 150 engaging with a rubber facing 170 on the cross bar 167, as shown in Fig. 3, so that the types are moved outwardly by the impact of the hammers and are then returned by their springs so as to clear the printing surface.

When it is desired to print or record the total at the foot of the column of the numbers which have been printed, the operation is as follows:—The total key 84 is first depressed, thereby raising the cam 14 into an inoperative position and lowering the cam 67 into an operative position. Upon now moving the rocking frames 15 and 29 forwardly the feeling levers 61 are turned so as to move their feeling fingers forwardly into engagement with the respective cams 57 and at the same time each feeling lever carries the adjacent key lever forwardly so that its particular stop shoulder 39 corresponding to the position of the trip cam 57 and its dial is moved into the path of the stop lug 34 of the controlling arm. After the key levers have been thus shifted forwardly into their respective positions corresponding with their dials, the continued forward move-

ment of the rocking frames causes the gear segments while in a retracted position out of engagement with the dial pinions to be depressed until each segment is arrested by the engagement of the stop lug on its controlling arm with the respective stop shoulder of its key lever, whereby each printing segment is raised so as to present the type carrier to the printing point which carries the type corresponding to the number registered on its companion dial. During the last part of the forward and downward rocking movement of the rocking frames the hammers are operated and the particular type at the printing line are impressed on the platen. Upon now swinging the rocking frames backwardly, the gear segments are raised while still in a retracted position out of engagement with their companion dial pinions, thereby permitting further numbers to be added to the total already registered on the dials. If however, it is desired to turn the dials back to zero, after the total of the added numbers has been printed or recorded the gear segments, while in the retracted lower position which they occupy while printing the totals, are moved forwardly into engagement with their respective dial pinions by the depression of the key 87. Upon now moving the rocking frames backwardly the gear segments are raised while in their forward position in engagement with their pinions, whereby each of the latter is turned backwardly and when the segments reach the end of their upward movement, the dials have been turned backwardly a number of spaces corresponding to the number on the dial, thereby turning all of the dials to zero.

Vertical ruling.

Mechanism is provided whereby vertical ruling may be produced on the recording surface, this mechanism being constructed as follows:—

203 represents an upright ruling lever which turns loosely on the supporting bar 12 and which is arranged between the dollars and dimes printing segments, as shown in Figs. 1, 11 and 13. The upper arm of the 115 ruling lever is provided with a vertical ruling blade 204 which is arranged close to the platen when in its upper position. The ruling lever is yieldingly held in this position by means of a spring 205 connected with the lower arm of the ruling lever and the movement of the latter toward the platen is limited by the engagement of its lower arm with the rear side of a rubber buffer 206 on the cross bar 167 similar to the rubber 170. 207 represents a pawl whereby the ruling lever is retracted and then released for permitting the same to deliver a blow against the recording surface for producing a vertical ruling impression thereon. This 130

pawl is pivoted at its lower end on the cross bar 151 and is yieldingly held with the hook 208 on its upper arm in engagement with a shoulder 209 on the ruling lever by means of a spring 210 which connects the lower arm of the ruling lever with the rod 162.

- In the uppermost position of the bar 167 the ruling pawl engages the shoulder of the ruling lever and upon depressing this bar, 10 the ruling lever is pulled downwardly by the ruling pawl. During this downward movement of the ruling lever and pawl, the front side of this lever engages with the upper arm of the pawl, and gradually crowds the 15 pawl forward until the pawl is disengaged from the shoulder of the lever. When the ruling lever is thus released from the pawl, the lever is quickly turned by the spring 205 in a direction for throwing its upper arm 20 upwardly, whereby its blade delivers a blow against the recording sheet or surface on the platen and produces a ruling impression thereon. During the last portion of the 25 subsequent upward movement of the ruling pawl 207 its hook again engages over the shoulder of the ruling lever. This construction of vertical ruling devices produces the vertical ruling in sections by successive blows of the ruling blade.
- 30 If desired vertical ruling may be produced by holding a stylus or lead pencil 211 against the recording surface by means of a stationary holder 212, as represented in Fig. 9, whereby continuous ruling is produced on 35 the recording surface or sheet as the sheet is fed past the same.

- Vertical ruling may also be produced by a 40 ruling disk 213 arranged to bear with one side against the recording surface and an inking wheel 214 supplying the ink to the edge of the ruling disk, as represented in Fig. 10.

Platen mechanism.

- 45 The mechanism whereby the platen is supported and operated and the sheet or other impression surface which receives the record is presented to the printing line, is constructed as follows:—
- 50 The frame of the carriage which supports the platen, paper and inking device consists of a transverse supporting sleeve 260 arranged in rear of the printing mechanism and provided at opposite ends with two upwardly and forwardly projecting arms 261 and with two upwardly and rearwardly projecting arms 262, as represented in Figs. 1, 2, 7, 11, 12 and 13. The supporting sleeve is arranged to slide transversely on a rod or 55 track 263 which is secured with its ends to the sides of the frame.
- 60 The platen is journaled in the upper ends of the front arms 261 of the paper carriage and is held in position at the printing line

by means of a catch 264 which engages with 65 its front hooked end over a transverse rod 265 arranged below the platen and secured with its ends to the sides of the main frame, as represented in Figs. 1, 2 and 13. This catch is yieldingly connected with the paper 70 carriage, so as to permit the platen to recede more or less from the printing mechanism for the purpose of adjusting the platen to the thickness of the sheet of paper or other 75 object which receives the impression and which is interposed between the platen and the printing types. This yielding connection forms no part of the invention claimed in the present application and will therefore not be described in full. This matter is 80 fully described and claimed in my pending divisional application Serial No. 243,444 to which reference is hereby made. For the purpose of the present application any suitable means may be employed for the purpose 85 of holding the platen in printing relation with the printing types.

The record-sheet is fed forwardly underneath the platen and upwardly in front of the same, so that the sheet passes the printing line. The sheet is pressed against the underside of the platen, in rear of the printing line, by a transverse presser roller 270 arranged below the platen and journaled with its ends in the front arms 261 of the 95 paper carriage.

Platen feed or line-spacing.

283 represents a platen feed lever which is pivoted loosely on the left end of the 100 platen shaft and which is provided on its rearwardly projecting arm with a pawl 284 which engages with a ratchet wheel 285 secured to the adjacent end of the platen, as represented in Figs. 1 and 7. 286 represents an intermediate actuating lever which is pivoted on the lower part of the front carriage-arm 261 which is adjacent to the ratchet wheel 285. The ratchet lever is connected with the intermediate lever by means 110 of a link 287 which is pivoted at its upper end to the rear arm of the ratchet lever and is provided at its lower end with a loop 288 which receives the rear arm of the intermediate lever. 289 represents a spring 115 which connects the front arms of the ratchet lever and intermediate lever. The upper end of this spring is connected with the front arm of the ratchet lever a greater distance from the pivot of the latter than the 120 distance between the connection of this spring with the intermediate lever and the pivot of the latter. By this connection of the spring 289, the leverage of the ratchet lever is greater than that of the intermediate 125 lever, which causes this spring, when both of these levers are free, to turn these levers simultaneously in the direction for rais-

The platen is journaled in the upper ends of the front arms 261 of the paper carriage and is held in position at the printing line

ing their rear arms, thereby moving the ratchet pawl upwardly or backwardly for taking up a new tooth on the ratchet wheel.

The ratchet pawl is yieldingly held in engagement with the ratchet teeth by means of a spring 290. The movement of the intermediate lever in the direction for raising its rear arm and moving the ratchet pawl backwardly is limited by means of a nose 291 formed on this lever and engaging with a stop on the adjacent arm of the carriage, as represented in Fig. 7.

The rocking motion of the intermediate lever is always the same, and in order to enable the same to turn the platen different distances, the rear arm of the intermediate lever is provided on its under side with a number of notches 292 which are arranged different distances from its fulcrum, and one or another of which is engaged by the lower end of the loop 288 on the connecting link 287. Upon engaging this loop with the notch of the intermediate lever nearest its axis, the ratchet pawl is shifted so that the platen is turned one line-space at a time; while upon shifting this loop into engagement with one of the outer notches of the intermediate lever, the platen will be turned forward by its ratchet mechanism a correspondingly greater distance by the operation of the machine.

The intermediate lever is turned in the direction for shifting the platen by a transverse bar 293 arranged below the front arm thereof, as represented in Figs. 1, 2, 7 and 13. This bar is supported upon the upper ends of two rock arms 294 which are mounted loosely with their lower ends on the cross bar 167. 295 represents a depending arm which is preferably formed in one piece with that one of the arms 294 arranged on the left hand side of the machine. This depending arm is provided with a nose which is arranged in rear of and in the path of the rocking frame 29.

During the last portion of the rearward movement of this rocking frame, it engages with the nose of the depending arm 295 and moves the same rearwardly, and the upper arms 294 connected therewith are moved forwardly, thereby causing the cross-bar 293 to be carried upwardly and turn the intermediate lever in the direction for feeding the platen and paper forwardly. During the forward movement of the rocking frame 29, the rock arms 294 are turned backwardly together with the intermediate lever and connecting parts by the spring 289 preparatory to feeding the platen forward the next space. As the line-spacing of the record sheet by feeding the platen occurs after each item is printed and in the same operation in which said item is printed, the printed record is fed up into visible position at each operation of the machine.

If desired, the platen may be turned by hand when it is desired to adjust the paper, this being effected by releasing the pawl 284 from the ratchet wheel and then turning the platen by means of a button 296 secured to one end of the shaft as shown in Figs. 1, 11 and 13.

The cross bar 293 extends a sufficient distance transversely of the machine so as to engage with the front arm of the intermediate rock lever 286 in all the positions to which the paper carriage can be shifted transversely in the machine.

Horizontally movable carriage.

The paper carriage is capable of sliding lengthwise on the rods 263 and 265 for presenting different parts of the paper to any particular type and is held in its adjusted position by a spacing device which consists of a graduated adjusting sleeve 301 and an adjusting catch 302, as represented in Figs. 2 and 12. The adjusting sleeve is revolvably mounted on the supporting sleeve 260 between the carriage frame arms 261 and is provided with two or more longitudinal series of stop notches or graduations 303, 304. The notches in each series may be equidistant and the notches in one series are spaced different from the notches in the other series, as shown in Fig. 21. The catch 302 is pivoted on the rod 167 and is yieldingly held in engagement with any one of the notches in the adjusting sleeve 301 by a spring 305. When it is desired to shift the carriage intermittently short distances lengthwise of the platen for writing narrow columns, the adjusting sleeve is turned so as to present its closely spaced notches to the catch, and the latter is shifted from one of these notches to another as the writing progresses. When wider columns are to be written the adjusting sleeve is turned so as to present correspondingly wider spaced notches to the catch. As shown in the drawings, only two series of adjusting notches are provided on the adjusting sleeve, but more series of notches may be provided if necessary.

Any suitable inking means may be employed, and the mechanism shown for this purpose is not fully described in this application, as this specific structure is not an essential part of the invention claimed herein. This specific inking mechanism is fully described in the parent application Serial No. 1,004 and is fully described and claimed in another divisional application Serial No. 254,065 to which reference is hereby made.

Any suitable full stroke mechanism may be provided to prevent the operator from making only a partial forward and backward stroke of the rocking frames 15 and 29, and the mechanism shown for this purpose is not fully described in this application.

This specific structure is not an essential part of the invention claimed herein, and is fully described and claimed in various combinations in the parent application Serial 5 No. 1,004 and in the divisional applications Serial Nos. 183,397 and 183,398, to which reference is hereby made.

- Any suitable mechanism may be provided to hold the keys when they are moved from 10 normal to operative position, and to release the number keys upon operating the operating mechanism and upon operating the total key, and the mechanism for this purpose is not fully described in this application.
- 15 This specific structure is not an essential part of the invention claimed herein and is fully described and claimed in the patent application Serial No. 1,004, and in other divisions thereof, to which reference is here- 20 by made.

The following is a sample of ruling performed by this machine:

25	1 25
	236 15
	000 00
	543 21
	780 61

30 *Adding in several columns with horizontally movable carriage.*

I claim:

1. In a calculating machine, the combination with a series of recording devices arranged side by side, of a vertical ruling device 40 arranged adjacent to said recording devices and adapted to produce vertical ruling relatively to the impression of the recording devices, a registering device co-operating with the recording devices, keys 45 pressible for controlling said recording and registering devices, and a hand-controlled operation-controlling member operable at a single operation to cause said recording devices to print a plurality of digits side-by-side and to effect ruling by said ruling device and to effect registering by said registering device.

2. The combination of a calculating mechanism, a rotatable platen, numeral types 55 operative with said platen and calculating mechanism so as to print on a record sheet backed by said platen and according to the calculations of said calculating mechanism, means for rotating said platen to line-space 60 said record sheet, a vertical ruling type, and means for causing said vertical ruling type to be impressed on said record sheet against said platen and concurrently with said numeral types so as to produce vertical ruling

in relation to the numbers printed by said 65 numeral types.

3. In a calculating machine, the combination of a plurality of accumulators, printing mechanism depressible number keys, a ruling device, a total key, and operating mechanism 70 for causing said printing mechanism to print the amounts accumulated on said accumulators under the control of said number keys and for causing said printing mechanism to print under control of said total 75 key the total accumulated on said accumulators and at either operation automatically operating said ruling device to print in relation to the matter printed by said printing mechanism. 80

4. The combination of calculating mechanism, a platen, numeral types for printing on a record sheet against said platen, selective mechanism for determining what shall be registered by said calculating mechanism and printed by said numeral types, operating mechanism for operating said calculating mechanism and numeral types according to the control of said selective mechanism, and a punctuation type automatically 90 operable by said operating mechanism for percussively printing punctuation on said record sheet in conjunction with the numbers printed by any of said numeral types. 95

5. The combination of integral-number printing types, fraction printing types, a platen for backing record material to receive impressions from any of said types, manipulative means for selecting which of said types shall print, a ruling type for printing 100 a rule in juxtaposition to numbers and fractions printed by any of said printing types, and operating mechanism common to said number and fraction printing types and said ruling type for effecting movement of 105 predetermined ones of said types for percussively printing thereby on said record material.

6. In a printing mechanism, the combination of a platen, a plurality of type-carriers arranged side-by-side, a plurality of character printing types on each of said type-carriers and operable for printing items, depressible keys for controlling the character printing types, a ruling type for 110 printing a vertical rule line between the printing effected by the types of two adjacent carriers of said plurality of carriers and operating mechanism for effecting operation of a type of each of a plurality of said 115 carriers according to the control of said keys and operation of said ruling type at a single operation of said operating mechanism.

7. In a printing mechanism, the combination of devices for printing items, means 120 for printing ruling with the printing of said items, key controlled setting devices for controlling setting of the first said devices with-

out controlling said rule printing means, and a hand-controlled operation controlling member for effecting printing by the first said devices and said means at a single operation of said member.

8. A machine comprising a horizontally movable carriage, means correlated with the carriage for carrying a record sheet, an operating member, depressible controlling keys separately operable number types a plurality of which may be impressed by a single operation of said operating member so as to effect printing on said record sheet according to the control of said number keys, means for detaining said carriage in position to locate said printing in a predetermined column space and operable for allowing said carriage to be moved for effecting printing in another column space, and means for printing a vertical rule line in connection with said printing in any of a plurality of horizontal positions of said carriage.

9. A machine comprising a platen operable to carry and line-space a record sheet, item printing types, depressible keys for controlling said types, operating means whereby said types are impressed against said record sheet on said platen so as to print items according to the control of said keys, and whereby said platen is moved to line-space said record sheet and a vertical rule member operable by said operating means to be impressed on said record sheet at each of a plurality of operations of said machine so that repeated operations may produce a vertical line the length of which is controlled by the number of operations of said machine when said rule member is operative.

10. In a printing machine, the combination of a platen movable for line spacing, a vertical ruling device coöoperative with said platen for producing lines of vertical ruling on a record sheet, and mechanism for holding said platen and ruling device relatively immovable in a direction at right angles to that in which it is moved for line spacing and operable for permitting movement of one relatively to the other longitudinally of said platen in a direction at right angles to that in which it is moved for line spacing.

11. In a printing mechanism, the combination of a platen, a plurality of printing types operable to print on a record-sheet backed by said platen, selecting mechanism for determining which of said types shall print on said record-sheet, a hand-controlled operation-controlling member for effecting printing by the selected types of said plurality of types, and a special type normally in such relation to such operating member that said member will automatically cause said special type to percussively print on said record sheet at each of a plurality of opera-

tions of said operation-controlling member for punctuating any of the numbers printed by said plurality of types.

12. The combination with the platen, of a member provided with a vertical ruling blade adapted to engage with the platen a device whereby said member is moved backwardly for retracting said blade from the platen, and a spring whereby said lever is moved forwardly for engaging the blade with the platen, substantially as set forth.

13. In a printing mechanism, the combination of a platen, types coöoperative with said platen, for printing on a record sheet, depressible keys for controlling said types, a device for detaining a pencil or stylus against movement laterally of its length while said pencil or stylus is being pressed against said platen, the construction and arrangement being such that said platen may be moved relative to said pencil or stylus to produce ruling on said record sheet.

14. In a recording machine the combination of a plurality of type; keys for controlling printing by said type; a rotatable cylindrical platen for supporting a record sheet to receive printing by said type and movable in line with its axis; and means mounted adjacent to said platen for holding a pencil or like recording instrument in such position that said recording instrument may be moved into coöperation with said platen whereby, by moving said platen, vertical and horizontal lines may be recorded on a record sheet supported thereon.

15. In a recording mechanism, the combination of a platen adapted to carry a record sheet, means for rotating said platen to line-space said record sheet, character printing types, keys for controlling said character printing types, and a ruling device uncontrollable by keys which control character printing and coöoperative with said platen for printing a vertical rule line on said record sheet upon rotating said platen.

16. In a machine, the combination of a plurality of sets of character types, a plurality of type-carriers one type-carrier for each of a plurality of said sets of types for supporting the same, means for supporting a record-sheet in printing relation to said types, key mechanism for controlling the matter to be printed on said record sheet by said sets of types, ruling mechanism operable for printing a ruling line on said record sheet between the printing done by the types of any pair of a plurality of pairs of adjacent sets of types, and operating mechanism for operating a plurality of said types according to the control of said key mechanism and operating said ruling mechanism, at each of a plurality of operations of said operating mechanism.

17. In a printing mechanism the combi-

nation of a platen, a plurality of printing types operable to print on a record sheet backed by said platen, a key controlled selecting mechanism for determining which 5 of said types shall print on said record sheet, a hand controlled operation-controlling member for effecting printing by the selected types of said plurality of types, and a special type normally in such relation to 10 said hand controlled operation-controlling member that said member will automatically cause said special type to print on said record sheet when any one of said plurality of types which may have been selected by 15 said selecting mechanism is caused to print by said hand controlled operation-controlling member.

18. In a printing mechanism the combination of a platen, a plurality of sets of 20 printing types each set comprising a plurality of types operable to print on a record sheet backed by said platen, a key controlled selecting mechanism for each of said sets of printing types for determining which type 25 of its respective set of types shall print on said record sheet, a hand controlled operation-controlling member for effecting printing by the selected types of said plurality of sets of types, and a special type arranged 30 to print between the printing effected by a type of each of a plurality of said sets of printing types and normally in such relation to said hand controlled operation-controlling member that said member will automatically cause said special type to so print 35 on said record sheet when any of such said

types of said plurality of sets of types which may have been selected by said selecting mechanism is caused to print by said hand controlled operation-controlling member. 40

19. The combination of an adding mechanism, a printing mechanism for printing the numbers added on said adding mechanism, keys for controlling said adding and printing mechanisms, punctuation printing 45 means operable to print punctuation with relation to the numbers added and printed by said adding and printing mechanisms, and universal means for causing said printing mechanism to automatically print the 50 total of the numbers added on said adding mechanism and for causing said punctuation printing means to print punctuation with relation to said total printed by said printing mechanism. 55

20. The combination of an adding mechanism, a printing mechanism for printing the numbers added on said adding mechanism, keys for controlling said adding and said printing mechanisms, rule printing means 60 operable to print ruling, and universal means for causing said printing mechanism to automatically print the total of the numbers added on said adding mechanism and for causing said rule printing means to print a 65 line of ruling with relation to said total printed by said printing mechanism.
